FOLDING CRATE

Filed Jan. 26, 1923

2 Sheets-Sheet 2

UNITED STATES PATENT OFFICE.

EMANUEL A. KAMERER, OF CEDAR, IOWA.

FOLDING CRATE.

Application filed January 26, 1923. Serial No. 615,117.

To all whom it may concern:

Be it known that I, EMANUEL A. KAMERER, citizen of the United States, residing at Cedar, in the county of Mahaska and State of Iowa, have invented certain new and useful Improvements in Folding Crates, of which the following is a specification, reference being had therein to the accompanying drawings.

10 This invention relates to a folding crate, and has for its object the construction of a simple and efficient crate that can be handled in a folded or knock-down condition, and which can quickly be adjusted to its open 15 position for receiving goods or products to be handled or shipped.

With this and other objects in view, my invention comprises certain novel combinations, constructions and arrangements of 20 parts as will be hereinafter described, illustrated in the accompanying drawings, and more particularly pointed out in the appended claims.

In the drawings:

25 Figure 1 is a perspective view of a crate constructed in accordance with the present invention.

Figure 2 is a sectional view, taken on line 2—2, Fig. 1, looking in the direction 30 of the arrows.

Figure 3 is a sectional view, taken on line 3—3, Fig. 2, looking in the direction of the arrows.

Figure 4 is a bottom plan view of my 35 crate.

Figure 5 is a perspective view of the crate, showing the same in a folded position,

Fig. 6 is a perspective view of a side of the crate.

40 Figure 7 is a plan view of the blank from which one section of the primary hinge device is formed.

Figure 8 is a blank view of one of the sections of the auxiliary hinge device.

45 Referring to the drawings by numerals, 1 designates the side sections as a whole, and 2 are the bottom sections connected to some of the side sections by hinges 3. Each side section comprises a plurality of horizontal slats or strips 4 connected together, at their ends, by one section of one of the primary hinge devices 5 and one section of one of the auxiliary hinge devices 6.

Each primary hinge device comprises 55 two similarly-constructed sections and it will

only be necessary to specifically describe one section: Each section is formed from a blank strip or piece of material (Fig. 7) and is folded along lines 7 and 8 to produce a substantially U-shaped body in cross section, into which body fits the ends of strips 4. At the ends of the section, and contiguous to opposite corners of said section, are outwardly extending lips 9; these lips 9 are adapted to be folded on lines 10, so that they rest in a horizontal plane, and receive rivets 11, by means of which rivets the two sections in each primary hinge device are pivotally connected.

There are two auxiliary hinge devices 6 used in the construction of my crate, just the same as there are two primary hinge devices employed; each auxiliary hinge device, like the primary hinge device, comprises two sections, each formed from a blank (Fig. 8); the blank is folded along lines 12 so as to produce a substantially U-shaped body (Fig. 6) similar to the U-shaped body of the sections of the primary hinge device. Extending from opposite ends and at the middle of the sections are apertured lips 13. These lips 13 are bent outwardly (Fig. 6), for receiving rivets 14, whereby the sections of the auxiliary hinge devices are pivotally connected together.

I employ two angle rest members 15, secured at opposite sides of the crate, upon which the hinged bottoms rest; when the device is in a set-up position, as shown in Figs. 1 to 4. It is to be noted that the lower lips 9 of the sections of the primary hinge device 6, are formed in the same horizontal (Fig. 6) plane with the lower flange of the angle members 15, so that these lower lips 9 and angle members 15 form a seat and "rest" flange upon which portions of the hinged bottom sections 2 rest when the device is in a set-up or unfolded position.

When the device is in a set-up position as shown in Fig. 1 and it is desired to fold the parts together, as shown in Fig. 5, all that is necessary is for the operator to press upward on the hinged bottom sections, to cause the same to close against the sides of the crate, and then by pressing inward upon the sides so as to place the auxiliary hinge devices at the middle (Fig. 5), the whole crate will easily and quickly fold together, for shipment or for storage purposes.

While I have described the preferred em-

bodiment of my invention, and have illustrated the same in the accompanying drawings, certain minor changes or alterations may appear to one skilled in the art to 5 which this invention relates, during the extensive manufacture of the same and I, therefore, reserve the right to make such alterations or changes as shall fairly fall within the scope of the appended claims.

10. What I claim is:

1. In a device of the class described, the combination of a plurality of side sections, a pair of primary hinge devices connecting some of said side sections together, a pair 15 of auxiliary hinge devices connecting some of said side sections together, each of said primary hinge devices comprising sections, each section of the primary hinge device comprising a U-shaped body provided at its 20 ends with overhanging, apertured lips, means connecting the lips of the sections of the primary hinge devices together, and hinged bottom sections secured to some of said side sections.
25. 2. In a device of the class described, the combination of a plurality of side sections, primary and auxiliary hinge devices pivotally connecting said side sections together, each primary hinge device comprising sections having U-shaped bodies and with in- 30 wardly extending overhanging lips at their ends, means pivotally connecting said lips together, angle rest members secured to some of said side sections and having por-

tions in alignment with some of the overhanging lips, and hingedly mounted bottom sections adapted to rest on said angle rest members and on some of said overhanging lips, substantially as shown and described. 35

3. In a device of the class described, the combination of side sections, hinge devices pivotally connecting said side sections, said hinge devices comprising sections provided with U-shaped bodies and with horizontal, apertured lips, means pivotally connecting 40 said lips together, and hinged bottom sections connected to some of said side sections.

4. In a device of the class described, the combination of a plurality of side sections, hinge devices pivotally connecting said side 45 sections, each hinge device including a pair of sections having U-shaped bodies and apertured angularly-disposed lips, means pivotally connecting said lips, and fold-up bottom sections supported upon some of 50 said side sections.

5. In a device of the class described, the combination of a crate provided at its corners with horizontal lips, angle rest members carried by said crate and provided with 55 portions in alignment with some of said lips, and a sectional bottom fastened to said crate and adapted to rest upon some of said lips and said angle rest members.

In testimony whereof I hereunto affix my 60 signature.

EMANUEL A. KAMERER.
